UNITED STATES PATENT OFFICE.

ERNESTO ROMANO, OF NEW YORK, N. Y.

TAPE-FEEDING ATTACHMENT FOR SEWING MACHINES.

Application filed April 26, 1922. Serial No. 556,729.

To all whom it may concern:

Be it known that I, ERNESTO ROMANO, a subject of the King of Italy, residing in the city, county, and State of New York, have 5 invented certain new and useful Improvements in Tape-Feeding Attachments for Sewing Machines, of which the following is a specification.

The present invention consists of a simple 10 and effective attachment for sewing machines for the purpose of feeding and tensioning tape as it is sewed to a piece of work in the ordinary sewing machine. The invention comprises a cylindrical shell formed 15 with tape slots at approximately its opposite sides and an inner slotted member adjustably mounted in said shell. The shell is mounted upon a suitable support by which it can be moved into and out of operative position 20 and is provided with means for engaging the presser foot of a sewing machine, so as to be held in working relation to the stitch forming mechanism of the machine. The support preferably carries a tape guide which 25 may be made in the form of a properly shaped and braced wire integral with the supporting arm. A device is also provided for adjusting the inner slotted member in the cylindrical shell for the purpose of determining the tension upon the tape as it 30 feeds through the device.

In order that my invention may be fully understood, I will first describe the same with reference to the accompanying drawing 35 and afterwards point out the novelty more particularly in the annexed claims.

In said drawing:

Figure 1 is a front elevation of the improved tape feeding and tensioning device 40 in operative relation to a sewing machine;

Figure 2 is a sectional side elevation of the same taken on the line 2—2 of Fig. 1;

Figure 3 is a sectional plan view of the same taken on the line 3—3 of Fig. 1;

Figure 4 is a view similar to Fig. 3 showing the attachment moved back out of the way into the position assumed when it is not in use;

Figure 5 is a detail sectional view taken 50 on the line 5—5 of Fig. 3;

Figure 6 is a detail longitudinal sectional view of the feeding and tensioning members;

Figures 7 and 8 are detail cross-sectional views of the same showing two positions of the parts.

Figure 9 is a detail perspective view of the tape tensioning device.

10 is a slotted base plate adapted to be secured to the bed plate of any ordinary sewing machine by means of a thumb screw 11 passing through the slot 10^a and threaded into the machine bed plate. 15 is an angle plate pivoted at 16 to base plate 10 and formed with a downwardly presented integral lug 17, which in the normal position of the attachment shown in Figs. 1, 2 and 3, engages the front edge of plate 10 to determine the operative position of the device. When the device is thrown into inoperative position as shown in Fig. 4, the lug 17 engages a shoulder 10^b formed by a slight cut-out in the plate 10. Angle plate 15 has a vertical projecting flange 15^a upon which is horizontally pivoted at 20 a supporting plate 25 having an integral limiting lug 26, which engages flange 15^a when member 25 is raised to its upward limit.

The support 25 has rigidly secured to it and projecting approximately horizontally from it a supporting arm 30 formed preferably of a steel wire or rod, which is suitably bent to provide a tape guiding loop 31 braced by portions 32, 33 and a projection 34 upon which is rigidly mounted the cylindrical shell 35 having diametrically opposite tape receiving slots 36 which extend longitudinally of the cylindrical shell and permit the passage of a tape diametrically through the shell.

40 is an inner guiding and tensioning member of approximately cylindrical shape, having a tape guiding slot 41 cut longitudinally in it so as to extend diametrically through it and a circular guiding head 42 journaled in the end of the shell 35 and its rear cylindrical portion 43 journaled in the inner end of shell 35. This member 40 is so mounted that it can be adjusted within the shell 35 to cause its tape guiding slot 41 to register with slots 36 of 100

the shell, or to move more or less out of registry for affording the desired tension upon the tape passing through the device.

- The inner member 40 is mounted upon the outer end of the rod 45, which is journalled in a boss 46 carried by an approximately semi-circular locking plate 47 rigidly mounted upon the supporting plate 25. Secured to the rod 45 is a spring finger lever 50 which is adapted to engage in any of the notches of the toothed segment 47^a formed upon the plate 47, whereby the inner member 40 can be secured in the desired adjusted position within the shell 35.
- 15 The drawing shows the device as it is applied to an ordinary sewing machine in which 60 represents a slightly modified presser foot having a needle receiving slot 61 and an inclined tape guiding slot 62.
- 20 When the tape guiding and tensioning device is in its operative position as shown in Figs. 1, 2 and 3 of the drawings, it will be observed that a curved finger 55 rigidly attached to shell member 35 engages the upturned toe of the presser foot 60, so that in the operation of the sewing machine the guiding and tensioning member will vibrate vertically with the presser foot, the device moving for this purpose upon the horizontal pivot 20. The tape to be sewed to a piece of work is fed from a spool or other source through the guide loop 31 and slots 36 and 41 of the tensioning device and the slot 62 of the presser foot and as it is sewed in place it feeds through said guide. When arranging the machine for a piece of work, the tape is threaded laterally into the registering slots of shell member 35 and inner member 40 through the open ends of said slots, and likewise into the guiding slot 62 of the raised presser foot;—the presser foot being then lowered and the sewing machine operated in the usual way. As the work starts, the operator adjusts the tension upon the tape 45 to suit the particular work by moving finger lever 50 to throw the guide slot of inner member 40 more or less out of registry with the guide slots 36 of the shell 35, the result of which operation is indicated in Figs. 7 and 8. When the device is out of use it can be moved to the position shown in Fig. 4 of the drawing.

I claim:

1. A sewing machine attachment comprising a base, a support pivotally mounted thereon, and a tape tensioning and guiding member movably mounted upon said support and provided with a finger shaped to engage the upturned end of the presser foot 55 of a sewing machine for retaining said member in operative relation thereto.
2. A sewing machine attachment comprising a base, an angle plate pivoted for horizontal movement upon said base, a support pivoted for vertical movement upon said

angle plate, and a tape tensioning and guiding member mounted upon said support.

3. A sewing machine attachment comprising a tape tensioning member, a braced supporting arm for said member, and a tape guiding loop on said arm, said braced supporting arm and tape guiding loop being formed of a suitably shaped continuous rod or wire.

4. A sewing machine attachment comprising suitably mounted relatively adjustable concentric members formed with tape receiving slots.

5. A sewing machine attachment comprising suitably mounted relatively adjustable concentric members formed with tape receiving slots open at the end for the insertion of the tape.

6. A tape tensioning attachment for sewing machines comprising a suitably mounted cylindrical shell formed with tape slots, and an adjustable inner concentric member formed with a tape slot.

7. A tape tensioning attachment for sewing machines comprising a suitably mounted cylindrical shell formed with tape slots, and an adjustable inner concentric member formed with a tape slot, the slots of said shell and inner member being open at one end for the lateral insertion of the tape.

8. A tape tensioning attachment for sewing machines comprising a suitably mounted cylindrical shell formed with parallel tape slots, a slotted inner member mounted concentrically within said shell, and means for adjusting said inner member in said shell.

9. A tape tensioning attachment for sewing machine comprising a suitably mounted cylindrical shell formed with oppositely arranged tape slots, a slotted inner cylindrical member having a smaller diameter than the inner diameter of said shell, said inner member being mounted concentrically within said shell and adjustable circumferentially therein.

10. A tensioning attachment for sewing machines comprising a support, an arm rigidly attached to and projected from said support, a slotted cylindrical shell secured upon said arm, a slotted inner member adjustably mounted in said shell, a rod carrying said inner member mounted to turn in said support, and an adjusting device connected with said rod.

11. A tensioning attachment for sewing machines comprising a support, an arm rigidly attached to and projected from said support, a slotted cylindrical shell secured upon said arm, a slotted inner member adjustably mounted in said shell, a rod carrying said inner member mounted to turn in said support, a toothed locking plate secured to said support, and an adjusting arm secured to said rod and adapted to engage said toothed locking plate.

12. A tensioning attachment for sewing machines comprising a support, an arm rigidly attached to and projected from said support, a slotted cylindrical shell secured upon said arm, a slotted inner member adjustably mounted in said shell, a rod carrying said inner member mounted to turn in

said support, interlocking devices mounted respectively upon said rod and said support for securing said inner member in desired 10 adjusted position, a base plate, and means for adjustably mounting said support upon said base plate.

ERNESTO RÓMANO.
